United States Patent Office

Des. 218,028
Patented July 14, 1970

218,028

VEHICLE SEAT

Thomas E. Lohr, Warren, Mich., assignor to Allied Chemical Corporation, New York, N.Y., a corporation of New York

Filed Apr. 18, 1969, Ser. No. 16,814

Term of patent 14 years

Int. Cl. D6—01

U.S. Cl. D15—8

FIG. 1 is a perspective rear view of a seat embodying my new design;

FIG. 2 is a side view of the seat of FIG. 1; and

FIG. 3 is a front perspective view of the seat of FIG. 1.

The side of the vehicle not shown is a mirror image of the side shown in FIG. 2.

I claim:

The ornamental design for a vehicle seat, as shown and described.
